CASKET HARDWARE

Raymond Larson, Chicago, Ill., assignor to Central Metallic Casket Co., Chicago, Ill., a corporation of Illinois

Application December 12, 1936, Serial No. 115,553

2 Claims. (Cl. 16—111)

This invention relates generally to new and useful improvements in casket hardware and has particular reference to casket handles.

Among the objects of my invention is to provide casket handles embodying novel features of construction, combination and arrangement of the parts and members thereof including rigid and simplified structural elements affording the production of such handles at a comparatively reduced cost of manufacture and facilitating the assembly and installation thereof.

It is also an object of the invention to provide a novel construction in the ornamental brackets of a casket handle which shall afford adequate structural rigidity and each of which brackets shall include an outwardly disposed integral portion adapted to constitute a supporting abutment arranged to receive and rigidly support an ornamental handle bar.

Another object of the invention resides in the construction of a casket handle embodying novel structural features in the ornamental brackets therefor, which include a bar-supporting portion formed integrally with and disposed outwardly and downwardly from the base plate thereof; the construction of such bar-supporting portion or extension being adapted to receive means for securing the handle bar thereto and additional means for rigidly securing the bracket to the casket wall; said brackets and bar-supporting portions being adapted to structurally resist the upward and outward movement of the handle bar during the carrying of the casket.

The invention which is shown in preferred embodiment in the attached drawing, is described in the following specifications and particularly pointed out in the appended claims.

In the drawing:

Fig. 1 is a side elevation of a portion of a casket showing a casket handle embodying my invention;

Fig. 2 is an enlarged rear view of one of the handle brackets showing an end portion of a handle bar attached thereto;

Fig. 3 is a vertical section through a portion of a casket wall showing an end view of the casket handle bar;

Fig. 4 is a vertical section taken on line 4—4 of Fig. 2;

Fig. 5 is a vertical section taken on line 5—5 of Fig. 2;

Fig. 6 is a horizontal section through one end of the handle bar taken on line 6—6 of Fig. 3;

Fig. 7 is a diagrammatic illustration of a handle supported on a pair of supports on a single

bracket; Fig. 7A is a vertical cross-section taken on line 7A—7A of Fig. 7.

In the embodiment of my invention shown in Figs. 1 to 6 inclusive, the metallic casket 15, partly shown in Fig. 1, has shown attached thereto on a casket handle embodying features of my improved combination and structural design and including a pair of brackets 16 having secured thereto a handle bar 18.

It may be stated that the invention is not limited to a handle of any particular ornamental or artistic design since the construction or structural features of the invention can readily be applied by those skilled in the art to handles of various other artistic designs, nor do I wish to be understood as limiting the invention to handles of metallic caskets as obviously the handles embodying my invention may readily be applied to caskets of wood or other materials.

In the handle design shown in Figs. 1 to 6, inclusive, the bracket 16 consists of an elongated laterally extending shell 16^A having an ornate exterior face 16^B and a rear marginal plane-aligned narrow face 16^C defining the general configuration of the shell and constituting a plane-aligned base which is adapted to be attached to the surface of a casket wall 15^A by means of bolts 19 which extend through the end portions of the shell 16^A, through the wall 15^A and a reinforcing bar 17 on the inner face of the wall 15^A.

In order to support the handle bar 18 the desired spaced distance from the side of the casket wall, the bracket 16 is formed with an outwardly disposed integral extension 16^D which is preferably of hollow formation and provided with an opening 16^E in its outer end adapted to receive a securing bolt 20 extending through such hollow extension 16^D, the casket wall 15^A and reinforcing bar 17.

The outwardly disposed extension 16^D is formed with a downwardly disposed integral end portion 16^F to thereby constitute a supporting abutment for the handle bar 18 which is positioned to abut the rear face of the end portion 16^F and the lower face of a substantially lateral wall portion 16^G of the extension 16^D. The specific design, construction or configuration of such extension 16^D could be varied to carry out its purpose or function which is primarily that of a supporting abutment adapted to support the handle bar 18 and to resist the tendency of any upward and outward movement of the handle bar relatively to the casket or its supporting bracket 16. Obviously, if the handle bar 18 be of circular or other cross-section, the extension 16^D could be

shaped to conform to a generally outwardly and downwardly curved body having an inner side or face suitably curved to receive the bar 18 of circular or other cross-section and thus resist any generally outward or upward directional pull on the handle bar when the casket is carried thereby. The particular cross-section shown in Fig. 4 is preferably formed as shown to accommodate a bar of rectangular or square cross-section, and in such design the depending end portion 16^F is substantially disposed relatively right-angularly to the generally outwardly projected extension 16^D.

The outwardly extended portion 16^D of the bracket is formed with a defining rear marginal narrow face 16^H plane-aligned with and merging into the marginal face 16^C. Upon tightening of the bolts 19 and 20 the bracket 16 will be securely fastened with its marginal face formations 16^C and 16^H to the side of the casket wall.

The particular design of handle bar 18 shown for illustrative purposes consists of a tubular shell 18^A which is adapted to receive end caps or closures 18^B also of tubular shell form. A reinforcing plug 21 of wood is fitted into the closure 18^B to extend to the place of the support of the handle bar on the bracket 16 and the plug 21 is adapted to receive the threaded end of the screw 22 which is projected through an opening 30 in the depending extension 16^F and through the shell portions 18^A and 18^B to thus retain the handle bar 18 against displacement from the bracket by its own weight or any accidentally applied pressure in the normal handling of the casket.

In the modification shown in Fig. 7 the bracket 16 is provided with a pair of spaced integral extensions 16^D adapted to support the handle bar 18.

It will be noted that the designs and constructions presented herein obviate the use of all fragile and costly hinges which are now com-

monly employed between the brackets and the handle bars of the usual casket handles.

I claim:

1. A casket handle comprising a plurality of spaced unitary brackets; a removably mounted handle bar secured to and connecting said brackets; each of said brackets comprising a plate portion having a front face and plane-aligned face formations on the rear face thereof adapted to engage the wall of the casket, an extension 10 formed integrally with said plate portion, said extension being disposed to extend forwardly and downwardly of said front face and having a rearwardly extending wall portion in plane-alignment with said plate face formations, means for 15 securing the plate portion to the casket wall, a bolt extending through the extension into securing engagement with the casket wall; said handle bar being mounted rearwardly of the downwardly extending portions of said extensions and 20 below the forwardly extending portions thereof; and means for securing the handle bar to each of said bracket extensions.

2. A casket handle comprising a plurality of spaced unitary brackets; a removably mounted handle bar secured to and connecting said brackets; each of said brackets comprising a plate portion having a front face and plane-aligned face formations on the rear face thereof adapted to engage the wall of the casket, an extension 30 formed integrally with said plate portion, said extension being disposed to extend forwardly and downwardly of said front face and having a rearwardly extending wall portion in plane-alignment with said plate face formations, means for 35 securing the plate portion to the casket wall, said handle bar being mounted rearwardly of the downwardly extending portions of said extensions and below the forwardly extending portions thereof; and means for securing the handle bar 40 to each of said bracket extensions.

RAYMOND LARSON.
